CLAIM

The ornamental design for a watering can, as shown and described.

DESCRIPTION

FIG. 1 is a perspective view of a watering can embodying my new design.

FIG. 2 is an elevational view taken from one side thereof, the opposite side being a mirror image of the side shown.

FIG. 3 is a front elevational view thereof.

FIG. 4 is a rear elevational view thereof.

FIG. 5 is a top plan view thereof, the bottom being plain and unornamented.

FIG. 1

FIG. 2

FIG. 4

FIG. 5

FIG. 3
